UNITED STATES PATENT OFFICE.

LEE S. CHADWICK, OF EAST CLEVELAND, OHIO, ASSIGNOR TO THE CLEVELAND FOUNDRY COMPANY, OF CLEVELAND, OHIO, A CORPORATION OF OHIO.

OIL-STOVE.

1,138,536.

Specification of Letters Patent.

Patented May 4, 1915.

Application filed July 23, 1914. Serial No. 852,611.

To all whom it may concern:

Be it known that I, LEE S. CHADWICK, a citizen of the United States, residing at East Cleveland, in the county of Cuyahoga and State of Ohio, have invented a certain new and useful Improvement in Oil-Stoves, of which the following is a full, clear, and exact description, reference being had to the accompanying drawings.

10 This invention relates to stoves wherein liquid fuel is employed, and has for its general object to provide a stove of this character with means whereby the liquid fuel supply may be replenished at any time in a 15 particularly convenient and efficient manner and without the necessity for and the annoyance of soiling the hands and without the consumption and consequent waste of an appreciable amount of time.

20 A further object of the invention is to provide a coöperating construction of stove and liquid fuel supply means whereby these results may be conveniently, efficiently, and economically attained.

25 I accomplish the foregoing results and others of a more limited nature to be pointed out hereinafter in and through the constructions illustrated in the drawings forming part hereof, wherein—

30 Figure 1 represents a front elevation of a stove constructed in accordance with my invention and having my liquid fuel supply means applied thereto; Fig. 2 a vertical sectional view corresponding to the line 2—2 of Fig. 1; Fig. 3 a sectional view of the lower portion of the stove, said view corresponding approximately to the line 3—3 of Fig. 4, a portion of the fuel supply tank being shown in elevation; Fig. 4 a trans-

plan and is provided with vertical side walls 14, extending from the upper ends of the flared bottom walls 15 therebeneath. The front bottom wall 16 of the sink extends through an opening in the front plate 10 and is provided at its outer or front end with an upwardly projecting wall 17, which is shorter than the side walls 14. The rear wall 18 of this sink is provided with an upwardly and outwardly curved splash apron 19. The forward portions of the side walls 14 of the sink are reinforced by plates 20. Firmly secured to said walls, and within these plates and the adjacent portions of the side walls, there is supported a hinge pin 21.

As will be apparent, particularly from Figs. 5 to 8 inclusive, the forward end of the drain sink projects through an opening in the front plate 10, which opening extends through the upper end of the plate and is of substantially the same width as the sink. In order that the lower portion of the plate 10 may serve as a firm support for the front end of the sink, said plate is flanged outwardly (as indicated at 10^b) directly beneath the overhanging portion of the sink and may be secured to such portion of the sink, as by means of solder.

30 A closure for the opening in the front plate is afforded by the sheet metal door 22, the same being preferably beaded about its edges, as shown at 22^a, and having a central vertical slot 23 therein, for a purpose to be explained hereinafter. The lower edge of the door is bent outwardly at right angles to its body portion and is provided with a sleeve 24 by which the door is hinged upon the pintle 21.

43 Carried by the inner surface of the door 22 is an open-ended, box-like carrier, for the liquid fuel dispensing receptacle, such box-like carrier comprising side walls 25, 26, an end wall 27, the remaining end wall being formed by the door 22. For convenience of description, the carrier will be assumed to be in the position shown in Fig. 6 in which position it is adapted to receive a dispensing receptacle prior to the application of the same to the distributing receptacle and the drain sink; and the terms "front", "back", "top" and "bottom" will be correspondingly applied to the parts of the carrier.

55 The side walls 25, 26 are extended below the bottom 28 of the carrier; as shown at 29, and these side wall extensions provided means for pivotally supporting an operating handle for the carrier. This operating handle, indicated at 30, is carried by a pair of arms 31, which are pivotally connected at their inner ends to the extensions 29, as indicated at 32. The arms 31 are connected by a transverse rod 33 which, when the carrier is in the position shown in Fig. 6, is adapted 85 to be received within notches 34 and which,

when the door 22 is closed and the carrier thereby caused to assume the position shown in Fig. 5, is adapted to be received within the notches 35 in the extensions 29. By means of the handle 30, the door and the carrier are swung upon the hinge pintle 21 to the position shown in Fig. 5, the handle 30 swinging through an arc of substantially 180°,—until the transverse rod 33 rests in the notches 35.

75 The corner of each wall extension 29, adjacent to the notch 34 therein, is flared outwardly, as indicated at 36 (see Figs. 5, 6 and 8) whereby the outturned portions of said wall extensions are adapted to bear against the arms 31 and, by their resilience, yieldingly support the handle in the position shown in Fig. 6, where it can be conveniently reached for the purpose of swinging the dispensing receptacle into operative relation to the distributing receptacle.

85 37 denotes a metal strip which may be secured in any convenient manner to the horizontally extending portion 22^b of the door, which metal strip overhangs the edge of the door and forms a supporting ledge for the bottom edge 38 of the liquid dispensing receptacle 39. It will be observed that the portion of the ledge which overhangs the receptacle 39 forms an acute angle with the body of the door 22 whereby, when the carrier and the door are swung to the position shown in Fig. 5, a channel 37 is provided at the bottom of the closed door.

95 The liquid dispensing receptacle is indicated at 39 and consists of a metallic can, which is adapted to be inserted, in inverted position, and to fit loosely within the carrier and is provided with a neck 40 which is internally threaded for the reception of a 100 threaded cap 41. Secured to this cap is a perforated cylindrical guide 42. Mounted within the cap and the guide is a valve stem 43 having a valve 44 thereon co-operating with a valve seat 45 in the cap and adapted 105 to close the port 46 through said seat. A spring 47, interposed between the valve body and the end of the cylindrical guide is adapted to hold the valve to its seat. Secured to the same end of the receptacle 39 as the valve 110 is an operating handle 47, said handle being offset a slight distance from the center of the receptacle. Within what will be the front wall of the dispensing receptacle (when the latter is in the position shown in Fig. 5) is a vertical recess 48. This recess 115 is narrow and relatively deep and extends substantially the full length of the receptacle 39. This recess forms a receptacle and a guard for a liquid level gage, said gage 120 consisting of a glass tube 49 having metal caps 50 at the ends thereof through which it is connected to the ends of the recess 48 and thereby to the interior of the dispensing receptacle. The arrangement is such that 125

85 130

the recess 48 will be in alinement with the slot 23 in the door, whereby the gage may be observed through said slot when the door is closed.

When it is desired to replenish the fuel supply, the condition of such supply being indicated by the gage 49, the operator swings the door 22 and the carrier to the position shown in Fig. 6. The dispensing receptacle 10 may now be removed from the carrier by the use of any approved form of lifter, the use of such a device being desirable in order to protect the hands of the operator from becoming soiled by contact with the receptacle, especially if the refilling operation should have to take place during the process of cooking or baking. Because of the fact that the receptacle 39 fits loosely within the carrier and that the handle 47 is offset from its center, the lifting of the receptacle will cause it to tilt sufficiently to enable the corner adjacent the ledge 37 to clear such ledge and permit the easy removal of the receptacle. A filled receptacle may then be substituted for the one removed and, because of its angle of inclination, due to the location of the handle as aforesaid, may be inserted in the carrier without the necessity of touching the same. When the receptacle rests upon the then bottom wall 28 of the carrier, it assumes an upright or vertical position, as shown in Fig. 6, with its upper rear corner beneath the ledge 37. As the operator swings the door 22 and the carrier upwardly 30 toward and into the position shown in Fig. 5, the receptacle moves by gravity toward the door, bringing the flange 38 into the channel 37^a, while the corner diagonally opposite the ledge 37 will bear against the wall 40 in such position as to project the neck 40 of the dispensing receptacle into the upper end of the distributing receptacle 11. Should it happen that, during this swinging operation, the flange 38 should not enter the channel 37^a, the opposite edge of the dispensing receptacle will contact with the splash apron 19 and the receptacle thereby be forced toward the door a sufficient distance to cause the flange to enter such channel. While the parts may be so proportioned as to cause the dispensing receptacle to rest upon and be wholly supported by the ledge 37, I prefer that the upper edge of the distributing receptacle 11 be at a higher elevation than said ledge when the parts are in the position shown in Fig. 5, so that the dispensing receptacle will rest securely upon the distributing receptacle.

It will be noted that the supply pipe 51, which conducts liquid fuel from the distributing receptacle 11 to the various burners, communicates with the bottom of said receptacle at one side of the center thereof, as indicated at 52. This leaves the central portion of the bottom of the receptacle 11

intact and in position to be impinged upon by the end of the valve stem 43, before the dispensing receptacle contacts with the upper edge of the distributing receptacle, whereby the valve 44 is lifted from its seat 70 45, permitting liquid fuel to flow from the receptacle 39 into the receptacle 11 until the level in the latter receptacle reaches the mouth of the neck 40 and seals the same against further discharge of liquid from the dispensing receptacle until such discharge is permitted by the lowering of the liquid level in the receptacle 11 to a point which will break the seal.

Upon the removal of the neck 40 from the receptacle 11, as the carrier is swung outwardly to the position shown in Fig. 6, a quantity of liquid will naturally adhere to such neck and either be thrown away from the dispensing receptacle by the centrifugal action induced by a rapid swinging movement of the carrier or be dropped from the neck upon the upper surface of the said receptacle if the swinging movement be a slow one. Any liquid that may be thrown away 90 from the dispensing receptacle by the centrifugal action referred to will be intercepted by the apron 19 and returned thereby into the sink, by the employment of a sink having a draining surface of greater area 95 than the cross sectional area of the carrier and arranged as shown in the drawing, it will be evident that any liquid which may accumulate on the dispensing receptacle and any liquid which may be within the carrier 100 will, when the carrier is in the position shown in Fig. 5 be delivered, through the sink and the opening 11^a, into the distributing receptacle.

Having thus described my invention, what I claim is:-

1. In a stove of the character described, the combination of a base, transverse plates projecting upwardly from said base, a liquid fuel distributing receptacle above said base 110 and interposed between said plates, a door adapted to swing upwardly and downwardly and pivoted at the front of said plates, a carrier for a liquid fuel dispensing receptacle supported by said door, a liquid fuel 115 dispensing receptacle on said carrier, one or more burners located outside the space formed between said plates, and a supply pipe communicating with the distributing receptacle and extending to said burner or 120 burners.

2. In a stove of the character described, the combination of a base having a compartment thereabove, a liquid fuel distributing receptacle in said compartment, a door for said compartment adapted to swing upwardly and downwardly, a carrier for a liquid fuel dispensing receptacle supported by said door, a liquid fuel dispensing receptacle on said carrier, one or more burners 130

located outside the compartment, and a supply pipe communicating with the distributing receptacle and extending to said burner or burners.

5. In a stove of the character described, the combination of a base, a pair of plates projecting upwardly from said base and forming opposite walls of a compartment, a plate extending across the space between the first mentioned plates and having a door opening therein, a door co-operating with said opening, a carrier mounted on said door, a liquid fuel dispensing receptacle adapted to be supported by said carrier, a liquid fuel distributing receptacle within the compartment, one or more burners located outside of said compartment, a supply pipe connecting the distributing receptacle with said burner or burners, and means whereby the liquid fuel in the dispensing receptacle may be delivered into the distributing receptacle when the former receptacle is brought into operative relation to the latter.

4. In a stove of the character described, the combination of one or more burners, a compartment, a liquid fuel distributing receptacle within said compartment, a supply pipe extending from said receptacle to said burner or burners, a door for said compartment, a carrier on said door, a liquid fuel dispensing receptacle adapted to be supported by said carrier, and connections whereby, when the door is closed, the dispensing receptacle will be brought into operative relation to the distributing receptacle to discharge its contents into the latter.

5. In a stove of the character described, the combination of one or more burners, a compartment, a liquid fuel distributing receptacle within said compartment, a supply pipe extending from said receptacle to said burner or burners, a carrier movable into and out of said compartment, a liquid fuel dispensing receptacle adapted to be supported by said carrier, and connections whereby, when the carrier is moved into the compartment, the dispensing receptacle will be brought into operative relation to the distributing receptacle to discharge its contents into the latter.

6. In a stove of the character described, the combination of one or more burners, a compartment, a distributing receptacle in said compartment, a supply pipe connecting said receptacle with said burner or burners, a door for said compartment, a carrier connected to said door and supported by said door, a liquid fuel dispensing receptacle adapted to be supported by said carrier, means whereby liquid fuel may be automatically discharged from the latter receptacle into the former receptacle when said door is closed, and means whereby the level of the liquid in the distributing receptacle may be maintained substantially constant.

7. In a stove of the character described, the combination of one or more burners, a compartment, a distributing receptacle in said compartment, a supply pipe connecting said receptacle with said burner or burners, a pivotally supported carrier adapted to be swung into and out of said compartment, a liquid fuel dispensing receptacle adapted to be supported by said carrier, means whereby liquid fuel may be automatically discharged from the latter receptacle into the former receptacle when said carrier is swung into the compartment, and means whereby the level of the liquid in the distributing receptacle may be maintained substantially constant.

8. In a stove of the character described, the combination of one or more burners, a compartment, a liquid fuel distributing receptacle within said compartment, a supply pipe connecting said receptacle with said burner or burners, a door for said compartment, a carrier on said door, and a dispensing receptacle adapted to be supported in said carrier and having a valve controlled outlet adapted to discharge into the distributing receptacle when the dispensing receptacle is brought into operative relation thereto by the closing of said door, the parts being arranged to provide a liquid seal for the discharge outlet from the dispensing receptacle into the distributing receptacle whereby a substantially constant level of oil is maintained in the latter receptacle.

9. In a stove of the character described, the combination of one or more burners, a compartment, a distributing receptacle in said compartment, a supply pipe connected to the bottom of said receptacle and extending to said burner or burners and communicating therewith, a vertically swinging door for said compartment, a carrier mounted on said door, a dispensing receptacle adapted to be supported within said carrier and having a discharge neck adapted to project into the distributing receptacle when the door is closed, a valve controlling said neck, and a spring arranged to seat said valve, said valve having a stem arranged to impinge against the bottom of the distributing receptacle, thereby to unseat the valve when the door is in closed position.

10. In a stove of the character described, the combination of one or more burners, a compartment having a door-opening, a liquid fuel distributing receptacle within the compartment, a liquid supply pipe communicating with said receptacle and with said burner or burners, a drain sink extending from said receptacle through the door opening and arranged to discharge into said receptacle, a door for said opening, a carrier supported by said door, and a liquid fuel dispensing receptacle adapted to be supported by said carrier and having a discharge

opening adapted to be brought into operative relation to the distributing receptacle when the door is closed.

11. In a stove of the character described, the combination of one or more burners, a compartment having an opening, a liquid fuel distributing receptacle within the compartment, a liquid supply pipe communicating with said receptacle and with said burner or burners, a drain sink extending from said receptacle through the opening and arranged to discharge into said receptacle, a pivotally supported carrier adapted to swing into and out of said opening, and a liquid fuel dispensing receptacle adapted to be supported by said carrier and having a discharge opening adapted to be brought into operative relation to the distributing receptacle when the carrier is swung into said opening.

12. In a stove of the character described, the combination of one or more burners, a compartment having a door opening, a liquid fuel distributing receptacle within the compartment, a liquid supply pipe communicating with said receptacle and with said burner or burners, a drain sink extending from said receptacle through the door opening and arranged to discharge into said receptacle, a door for said opening and hinged on a horizontal axis above such portion of said sink, a carrier supported by said door, and a liquid fuel dispensing receptacle adapted to be supported by said carrier and having a discharge opening arranged to be brought into operative relation to the distributing receptacle when the door is closed.

13. In a stove of the character described, the combination of one or more burners, a compartment having an opening, a liquid fuel distributing receptacle within the compartment, a liquid supply pipe communicating with said receptacle and with said burner or burners, a drain sink extending from said receptacle through the opening and arranged to discharge into said receptacle, a carrier hinged on a horizontal axis above such portion of said sink, and a liquid fuel dispensing receptacle adapted to be supported by said carrier and having a discharge opening adapted to be brought into operative relation to the distributing receptacle when the door is closed.

14. In a stove of the character described, the combination of one or more burners, a compartment having a door opening, a liquid fuel distributing receptacle in said compartment, a liquid fuel supply pipe communicating with said receptacle and with said burner or burners, a drain sink surrounding said receptacle and having a splash apron projecting upwardly therefrom and arranged to discharge into said receptacle, a door adapted to close said door opening, a

carrier mounted on said door, and a liquid dispensing receptacle adapted to be supported by the carrier and having a discharge opening arranged to supply liquid fuel to the distributing receptacle when the door is closed.

15. In a stove of the character described, the combination of a burner, a liquid fuel distributing receptacle, a liquid fuel supply pipe communicating with said receptacle, and said burner, a pivotally supported carrier, a liquid dispensing receptacle adapted to be supported by the carrier and having a discharge opening arranged to supply liquid fuel to the distributing receptacle when the former receptacle is swung into operative relation to the latter receptacle, and means for intercepting and delivering to the latter receptacle liquid that may be discharged outside said receptacle from the carrier or the dispensing receptacle.

16. In a stove of the character described, the combination of a burner, a compartment having a door opening, a liquid fuel distributing receptacle in said compartment, a drain sink arranged to discharge into said receptacle and having a portion of its draining surface projecting through the door opening and having another portion projecting in the opposite direction from the receptacle and provided with a splash apron, a door for the said opening hinged on a horizontal axis above the portion of the drain sink which projects through said opening, a carrier on said door, and a liquid dispensing receptacle adapted to be supported within the carrier and having a discharge opening arranged to supply liquid fuel to the distributing receptacle when the door is closed.

17. In a stove of the character described, the combination of a burner, a liquid fuel distributing receptacle, a drain sink arranged to discharge into said receptacle, a carrier pivotally supported on a horizontal axis above a portion of the drain sink, a liquid dispensing receptacle adapted to be supported by the carrier and having a discharge opening arranged to supply liquid fuel to the distributing receptacle when the carrier is swung upwardly above the latter receptacle, and means on the opposite side of the latter receptacle from the carrier axis for intercepting liquid that may be discharged by centrifugal action from the carrier and the former receptacle.

18. In a stove of the character described, the combination of a burner, a compartment, a distributing receptacle within said compartment, a supply pipe communicating with the receptacle and with said burner, a door for said compartment, a carrier mounted on said door, a liquid fuel dispensing receptacle adapted to be supported by said carrier and having a liquid level gage in the wall thereof which is presented toward said door, said

- door having an opening adapted to register with said gage, and connections whereby the dispensing receptacle may discharge into the distributing receptacle when the door is closed.
19. In a stove of the character described, the combination of a burner, a distributing receptacle, a supply pipe communicating with the receptacle and with said burner, a carrier that is capable of being moved above the distributing receptacle, a liquid fuel dispensing receptacle adapted to be supported by said carrier and having a liquid level gage in a wall thereof, said carrier having an opening adapted to register with said gage, and connections whereby the dispensing receptacle may discharge into the distributing receptacle when the carrier is moved thereabove.
20. 20. In a stove of the character described, the combination of a burner, a compartment, a distributing receptacle within said compartment, a supply pipe communicating with the receptacle and with said burner, a door for said compartment, a carrier mounted on said door, a liquid fuel dispensing receptacle adapted to be supported by said carrier and having in one wall thereof a longitudinally
- extending recess, a liquid level gage in said recess, the door having an opening adapted to register with said recess, and connections whereby the dispensing receptacle may discharge into the distributing receptacle when the door is closed.
21. In a stove of the character described, the combination of a burner, a distributing receptacle, a supply pipe communicating with the receptacle and with said burner, a movably supported carrier, a liquid fuel dispensing receptacle adapted to be supported by said carrier and having in one wall thereof of a longitudinally extending recess, a liquid level gage in said recess, the carrier having an opening adapted to register with said recess, and connections whereby the dispensing receptacle may discharge into the distributing receptacle when moved into operative relation thereto by the movement of the carrier.
- In testimony whereof, I hereunto affix my signature in the presence of two witnesses.
- LEE S. CHADWICK.
